UNITED STATES PATENT OFFICE.

OSCAR E. ERICKSON AND HJALMAR OLSON, OF CHICAGO, ILLINOIS.

COLLAPSIBLE BABY-CARRIAGE.

1,189,244.

Specification of Letters Patent.

Patented July 4, 1916.

Application filed July 19, 1915. Serial No. 40,692.

To all whom it may concern:

Be it known that we, OSCAR E. ERICKSON and HJALMAR OLSON, citizens of the United States, and residents of Chicago, in the county of Cook and State of Illinois, have invented certain new and useful Improvements in Collapsible Baby-Carriages, of which the following is a specification.

This invention relates to that kind or class of vehicles which are designed to be folded or collapsed for shipping or storage purposes, and to be set up for use as a baby carriage.

The object of this invention is to obtain a device which, when folded or collapsed will have the appearance of a small suit case, provided with a handle for carrying it, which is easily set up for use as a carriage, and when set up will have a neat and sightly appearance; and which in its set up form is stable, durable, and not liable to become broken, or get out of order.

We have illustrated a device embodying this invention in the drawings accompanying and forming a part hereof in which—

Figure 1 is an elevation of the device in a collapsed or folded form. Fig. 2 is a side elevation of the device in its set up form, for use as a baby carriage. Fig. 3 is a rear elevation in the set up form, but with the handle and awning of the device not extended. Fig. 4 is a plan view of the principal parts of the device in a partially set up condition. Fig. 5 is an end view of the parts forming the sides of the case obtained when the device is collapsed and the seat and back obtained therefrom when the device is set up, with the levers which are attached to said parts, said parts being in the same relative position as in Fig. 4. Fig. 6 is a section of one of the levers of the device, on line 6—6 of Fig. 5, viewed in the direction indicated by the arrows; and Fig. 7 is a cross section of an additional lever, taken on line 7—7 of Fig. 5, also viewed in the direction indicated by the arrows.

A reference letter applied to designate a given part indicates said part throughout the several figures of the drawings, wherever the same appears.

A, B are bases which form the outside of the receptacle resembling a suit case, which is obtained when the device is folded, or collapsed, as is illustrated in Fig. 1, and

obtained when the device is set up, as is illustrated in Fig. 2.

C is the handle of the device, and is movably mounted in part B, as is hereinafter more fully described.

The outer face of part A, (when the device is collapsed) forms the upper face of the seat of the carriage, (when the device is set up); and the outer face of the part B, (when collapsed) forms the inner face of the back of the carriage, (when set up). When the device is collapsed there are exposed to view, at the ends of the receptacle resembling a suit case, the levers D, E, and links F. Lever D forms a riser to lever E, when the device is set up, and said lever E forms an arm rest at said time. The parts A and B are pivotally secured together by the links a and pins or pivots b. Riser D is attached to part A by pin or pivot d, lever E is attached in the same way to part B by pin or pivot e, and levers D and E are joined together by pivot or pin e¹. Link F, which is pivotally attached to lever D by pivot d¹, is provided with a pin or projection G at its free end, and said pin is movable in slot H in lever E. Pin G also fits in the respective cross slots h, h¹, (hereinafter termed notches). Slots H, and branch or cross slots h, h¹, are hereinafter referred to as notched slots.

The several levers D, E, and links F and a, are attached to the parts A, B, and to each other, in such manner as to permit of the turning of said parts A, B on links F, from a position where said parts are in parallel planes, as in Fig. 1, through an arc of approximately two hundred and seventy degrees and into the position in which they are illustrated in Fig. 2, so long as the pins or abutments G are free to slide in slots H, that is, so long as said pins are not in one or the other of the notches h, h¹. When said pins G are in said notches h the risers D and arms E are rigidly held thereby, together with seat formed by part A and back formed by part B, in the position in which said parts are illustrated in Fig. 2, by full lines; and when said pin G is in notch h¹ said parts are maintained in the position in which they are indicated by broken lines in said figure.

I are wheel frames and J are wheels rotatably mounted in frames I. Frames I are pivotally attached to part A by hinges K.

k is the pintle of hinge *K*, and *X* are abutments on the part of hinge *K* which is riveted to said part *A*. The abutments *X* are spaced so that when the wheel frame 5 *I* is turned on hinge *K*, so as to be at an angle of ninety degrees from said part *A*, said wheel frame is between said abutments. The wheel frames *I* are respectively made 10 of strap sheet metal which is bent to obtain two parallel sides, between which wheel *J* turns, (being mounted on an axle at or near one end of said sides); said bending being substantially as follows:—Starting at the end which is lettered *L*, (see Fig. 3), it extends 15 to hinge *K*, where it is bent around pintle *k*, to an angle of one hundred and eighty degrees, and extends back toward the end *L* to a point which is a greater distance from said end than the radius of the 20 wheel mounted in the frame, when it is again bent to an angle of ninety degrees, to obtain the part which is lettered *L*¹; it is again bent to an angle of ninety degrees 25 to obtain part which is lettered *L*², (which is substantially parallel with the sides of the frame), and is again bent to obtain the part *L*³, and the opposite side of the frame. The part *L*² is adapted to engage, or to be engaged by, the end *M* of riser *D*, 30 when the several parts of the device are in the position illustrated in Fig. 2, and thereby the wheel frames *I* are held firmly in their set up position, that is, at right angles to part *A*.

35 *N* is a wheel frame which is pivotally attached to part *A* by hinges *n*.

O are wheels in frame *N*.

P is a two part lever or link. The parts 40 of lever *P* are lettered *p*, *p*¹, and are pivotally attached together by pin *p*². Part *p* of said lever is pivotally attached to part *A* by pin *p*³, and part *p*¹ is pivotally attached to frame *N* by pin *p*⁴.

*p*⁵ is a pin which limits the pivotal movement 45 of parts *p*, *p*¹ on pin *p*², when the device is set up, (as in Figs. 2 and 3).

Q is a foot rest which consists of side bars which are longitudinally movable in part *A*, the end bar *q*, and the apron *q*¹.

50 Referring to handle *C*, said handle is mounted between bars *R*, which are slidably mounted in part *B*.

r, *r*¹, are bends in bars *R*, to obtain the diagonally extending parts *r*², which extend over on to part *A* when the device is collapsed.

55 *S*, (see Figs. 2 and 3) are pins or abutments on the under side of part *r*², of bars *R*; and when the device is collapsed said abutments *S* are forced into apertures *S*¹ of bar *q*. When said pins are in said apertures the parts *A* and *B* are latched thereby together, so that they cannot turn on links *a*.

When bars *R* are drawn out of the part *B* 60 said pins *S* are drawn out of apertures *S*¹,

(see Fig. 2 for said apertures indicated by broken lines in bar *q*), and the parts *A*, *B*, can be turned on said links.

T, (Fig. 2) and *T*¹, (Fig. 3) are apertures in bars *R*, and *U*, (Fig. 3) are longitudinally movable rods which are mounted in part *B*, and *u* is a spring which yieldingly holds said rods in an advanced position. Bars *U* are bent near the ends to obtain parts *U*¹, which extend through slots 75 *u*¹ in said part *B*, into position to be grasped and brought together against the resiliency of spring *u*, thereby retracting the rods *U*. When rods *U* are advanced the ends thereof are in one or the other of the apertures 80 *T*, *T*¹. When the device is collapsed and the handle *C* forced as near to the parts *A*, *B*, as possible, with the pins *S* in apertures *S*¹, the aperture *T* is in position so that said rods *U* may enter them, and as 85 said rods enter said apertures *T* the bars *R* are latched, so that they cannot be drawn out of said part *B* until the ends *U*¹ are forced together, to retract said rods *U* from said apertures *T*. When the device is set 90 up and the handle *C* and bars *R* are drawn out the apertures *T*¹ are in position so that rods *U* may enter said apertures, and thereby latch said bars *R* in said position.

95 *V*, *V*¹ are **U**-shaped bars, forming the frame of an awning. Bar *V* is pivotally attached to part *B* by rods *U* which extend through apertures in said bars *V*. The sides of bar *V*¹ respectively comprise an additional part (*V*²) which is pivotally attached 100 to the ends of bars *V*¹ by pin *V*³, and said bars *V*² are pivotally attached to the sides of bar *V* by pins *V*⁴.

*V*⁵ is the textile fabric of the awning.

105 *W* is a strap which is attached to the riser *D*, on one side of the device and to the riser on the other side, to provide means for holding an infant in the device when the same is in the condition which is illustrated in Fig. 2.

110 To set up the device it is held so that the pins *G* will not leave slot *H* to enter slots *h*, *h*¹, and parts *A*, *B*, are turned on links *a*. As the device becomes partially "set up" the part *A* is turned so that wheel frames 115 *I* will fall into position extending downward at right angles to said part *A*, and the completion of the "set up" is accomplished. As said setting up is completed the pins or abutments *G* will be in position to drop 120 into slots *h*, and link *F* will then hold the several parts together in said set up position. The handle *C* is drawn out; the foot rest is drawn out, and the awning is turned on its pivots into position over the seat of 125 the vehicle. The device is then ready for use as a carriage. Care must be taken that the ends *M* of risers *D* properly engage with the part *L*² of frame *I*, when the device is being set up.

We claim:—

1. In a collapsible baby carriage, a two part receptacle, a link pivotally attached at its ends to said parts, an arm pivotally attached at one end to one of said parts and a riser to said arm pivotally attached to the other of said parts, and said arm and riser pivotally attached together, a notched slot in said arm, a connecting link pivotally attached to said riser, and a pin in said connecting link adapted to fit in said notch when said parts of the receptacle, said arm and riser are all in a pre-determined position, to maintain said parts in said position, all operatively combined.

2. In a collapsible baby carriage, a two part receptacle, links pivotally attached at their ends to said parts, arms pivotally attached at the ends thereof to one of said parts, and notched slots in said arms, risers pivotally attached to the other of said parts, said arms and risers pivotally attached together, connecting links pivotally attached to said risers, and pins in said connecting links, said pins adapted to move in said slots and to fit in said notches, wheel frames pivotally attached to one of said parts of the receptacle to move in a plane at right angles to the plane in which said risers move when turned on the several pivots thereof, said wheel frames and said risers adapted to engage when in a pre-determined position, to maintain said wheel frames in said turned position, all operatively combined.

3. In a collapsible baby carriage, a two part receptacle, links pivotally attached to said parts, arms pivotally attached to one of said parts, said arms provided with notched slots, risers pivotally attached to the other of said parts, and to said arms, links attached to said risers, pins on said links adapted to move in said slots and to fit in said notches, wheel frames hinged to the said part which is provided with said risers, said risers and wheel frames adapted to engage when in a pre-determined position to maintain said wheel frames in said position, an additional wheel frame pivoted to said part which is provided with said risers, and a two part link pivoted to said additional wheel frame and to said last named part of the receptacle, combined as set forth.

4. In a collapsible baby carriage, a two part receptacle, links pivotally attached to said parts, said parts adapted when in a pre-determined position to form the back and seat of a baby carriage, arms pivotally attached to said back part, said arms provided with notched slots, risers pivotally attached to said seat part and to said arms, links pivotally attached to said risers, pins on said last named links, said pins adapted to move in said slots and to fit in said notches, wheel frames pivotally attached to said seat part to be movable in a plane at right angles to

the plane in which said risers move, and said risers adapted to engage with said wheel frames, when in a pre-determined position, and to maintain said wheel frames in an operative position, in combination with an additional wheel frame pivoted to said seat part, and a handle longitudinally movable in said back part, with means to hold said handle in predetermined position.

5. In a collapsible baby carriage, a two part receptacle, links pivotally attached to said parts and arranged to permit said parts to be moved into parallel planes and into planes substantially at right angles, with the faces of said parts which form the sides of the receptacle when in parallel planes forming the upper face of a seat and the inner face of a back when said parts are substantially at right angles, in combination with arms pivotally attached to said back part and risers pivotally attached to said seat part and to said arms, said arms provided with notched slots, links pivotally attached to said risers, abutments on said last named links, adapted to move in said slots and to fit in said notches, wheel frames pivoted to said seat part, said risers and wheel frames adapted, when both thereof are in a determined position to engage to maintain said wheel frames in said determined position, and an additional wheel frame collapsibly mounted on said seat part, with means to hold said additional frame in a pre-determined position.

6. In a collapsible baby carriage, the combination of a two part receptacle, connecting links pivotally attaching said parts together, a handle movably mounted in one of said parts, and apertures in one side of the other of said parts, abutments on said handle adapted to fit in said apertures, longitudinally movable rods mounted in the one of said parts which is provided with said handle, means to yieldingly hold said rods in an advanced position, and said handle provided with apertures positioned to receive said longitudinally movable rods when in said advanced position, all arranged to hold said handle in a closed position and said parts in a closed position when said rods are advanced and in said apertures therefor.

7. In a collapsible baby carriage, the combination of a two part receptacle, connecting links pivotally attaching said parts together, said parts movable on said links from substantially right angles into parallel planes, arms pivotally attached to one of said parts and risers pivotally attached to the other of said parts and to said arms, means to hold said arms and risers in a pre-determined position when said parts are substantially at right angles, to maintain said parts in said position, wheel frames hinged to one of said parts and adapted to be moved into a pre-determined position and engage-

able, when in said pre-determined position with said risers to be thereby maintained in said pre-determined position, an additional wheel frame, and a two part link connected 5 to said additional wheel frame and to the part of said receptacle which is provided with the first named wheel frames.

8. In a collapsible baby carriage, the combination of a two part receptacle, connecting links pivotally attaching said parts together, to permit the same to be moved into parallel planes and into planes which are at substantially right angles, with the outer faces when in parallel planes forming 10 the upper and inner faces of the seat and

back formed when said parts are in said planes at substantially right angles, means to maintain said parts in said planes at substantially right angles, bars adapted to form the side bars of an awning pivotally attached to the part forming said back, and bars slidably mounted in the part forming the seat and adapted to form the side bars of a foot rest. 20
